UNITED STATES PATENT OFFICE.

RICHARD K. MOSLEY, OF EAST ORANGE, NEW JERSEY.

DELIVERY-CABINET.

1,358,866.

Specification of Letters Patent. Patented Nov. 16, 1920.

Application filed August 14, 1917. Serial No. 186,151.

To all whom it may concern:

Be it known that I, RICHARD K. MOSLEY, a citizen of the United States, residing in East Orange, county of Essex, State of New Jersey, have invented certain new and useful Improvements in Delivery-Cabinets, of which the following is a specification.

My invention relates to a delivery cabinet in which is temporarily deposited commodities usually delivered to a household, and the principal objects of the invention are to provide a cabinet which is automatically opened by the opening of the tradesman's door upon the exterior of the wall in which 10 the cabinet is mounted and is automatically locked on the closing of said door after it has been once operated from the exterior of the wall, so that the door which gives access to the cabinet from the exterior can 15 not again be opened without resetting the mechanism from a point upon the interior of the wall. Further objects of the invention are to provide a substantial device of 20 this class which affords great safety for the delivery of goods by tradesmen or messengers, from a point exterior to the room from 25 which legitimate access is had to the cabinet and without giving such person access to the room. With these and other objects in 30 view my invention consists in the various novel and peculiar arrangements and combinations of the several different parts of the mechanism, all as hereinafter fully set forth, and then pointed out in the claims.

I have illustrated a type of my invention in the accompanying drawings, wherein: Figure 1, is an elevation of the cabinet viewed from the side toward the interior of the room, and with the outer door closed; 40 parts of the frame work above and below the revolving receptacle being broken away to show the respective bearings at the upper and lower ends of the revolving receptacle and also the locking device at the lower end 45 of the receptacle and the connecting rod for turning the receptacle on its axis automatically when the outside door is opened.

Fig. 2, is an enlarged isometric view of the locking means for the revolving receptacle and the outer door, partly in section.

Fig. 3, is a similar view to that shown in Fig. 2, but with the locking parts in different positions from those shown in Fig. 2.

Fig. 4, is an enlarged detail view of the 55 divided bearing for the upper end of the revolving receptacle together with the spring

locking device for holding the two parts of the bearing together.

Fig. 5, is a vertical sectional view of the upper part of the device.

Fig. 6, is a horizontal sectional view of the device with the outer door in closed position and also shown in the open position in dotted line, the plane of the section being indicated by the dotted line 6—6 in Fig. 1. 60

Fig. 7, is a vertical sectional view of the lower part of the device showing the lower end of the revolving receptacle together with the locking means and the connecting rod for revolving the receptacle. 65

Referring to the drawings, in which like numerals of reference designate like parts throughout, 1 indicates the exterior casing which is adapted to be built into an ordinary wall 2, so as to provide the interior 75 opening 3, and an exterior opening 4, the latter being closed by a door 5, hinged at 6, to a fixed point on the wall.

Within the casing 1, is mounted the delivery receptacle 7, which revolves on a vertical axis and in the present construction is shown in the form of a closed cylinder having the single opening 8, in one side equal to about a quarter of the periphery of the cylinder and through which the articles are 80 deposited within the cylinder and also removed therefrom. The lower bearing of the cylinder comprises a centrally located socket piece 9, secured upon the bottom of the cylinder into which projects the short cylindrical pin 10, fixed upon the bottom of the inclosing casing 1. The upper bearing of 85

the receptacle comprises a short cylindrical pin 11, secured to the upper side of the receptacle at the center thereof and this pin 90 is provided with a shoulder 12, against which rests the lower end of the divided bearing 13, which is divided longitudinally into two parts, forming two half cylinders, one of which is secured to the casing 1, and 95 the other part is hinged to the first mentioned part at 14, the hinged part being provided with a lever 15, for separating the two parts of the bearing or closing one 100 against the other, as indicated in Fig. 4. 100

The lever 15, is provided with a spring latch 16, pivoted at 17, to the lever and engaging a piece 18 on the fixed part of the bearing 13. The full line position in Fig. 4, shows the latch closed and it may be opened by 110 pressing the end 19, of the latch toward the lever 15, by hand whereupon the parts may

be swung into the dotted line position so as to open the bearing in order that the pin 11, may be swung laterally away from the bearing to dismount the cylinder. This 5 mounting also permits sufficient vertical movement of the cylinder after the pin is swung out of the bearing, to allow the cylinder to be lifted out of its bearing at the lower end in order to remove it from the 10 surrounding casing whenever it is desired to clean or repair the device.

The exterior door 5, is so connected with the revolving cylinder 7, that when the door is closed, as shown in the drawings, the 15 hand opening 8, in the cylinder is presented to and registers with the opening 3, upon the interior of the wall or room, and when the door 5, is swung open, into the dotted line position, shown in Fig. 6, the cylinder 20 is turned through a half circle to present the hand opening 8, in registration with the exterior opening 4, for the reception of articles from the exterior of the wall or room. In the present construction I control the 25 door and receptacle by connecting the revolving cylinder to the door with a link or rod 20, having one end pivoted at 21, to the door and the other end pivoted at 22, to the bottom of the cylinder at a point 30 near its circumference, these parts being so adjusted and related that, when the door is closed the hand opening of the cylinder is open to the interior and when the door is opened, the hand opening is presented to 35 the opening upon the exterior of the wall.

I provide the cylinder with an automatic locking means which may be set only from the interior of the wall or room to permit the exterior door being opened and closed 40 once. The succeeding opening operation of the door can only be effected after the device is reset from the interior.

The automatic locking means comprises a suitable casing 23, having a face plate 24, 45 through which operate the latch 25, and the latch-reset 26, which are beveled in opposite directions. The latch 25, is provided with a spring 27, which keeps the latch normally pressed outwardly, as indicated in Figs. 1, 50 2, and 7, and the latch is retracted by means of a plunger 28, which slides at right angles to the movement of the latch and has upon its underside an inclined surface 29, which engages a correspondingly inclined surface 55 30, on a lug 31, projecting laterally from the latch. When the plunger is forced inwardly by means of its handle 32, the incline 29, of the plunger slides over the incline 30, of the lug and forces the latter 60 downwardly into the position shown in Fig. 3, in which position the flat surface 33, on the underside of the plunger engages the upper part 34, of the lug and holds it down as shown in Fig. 3.

The automatic latch-reset 26, operates 65 downwardly by gravity and is normally in its retracted position and it is raised in the same movement of the plunger that retracts the latch 25, the plunger being provided on its inner end with the inclined piece 35, 70 which engages the inclined part 36, on the under side of a lug 37, projecting laterally from the latch-reset 26. The extreme end of the inclined part 35, is bent at 38, into horizontal position and acts somewhat as a 75 lever upon the lower end of the lug 37, when the inclined part collides with it and insures the lifting movement of the latch. The latch and latch-rest coöperate with the fixed lugs on the under side of the revolving 80 cylinder. When the outer door is closed and the latch 25, is shot, its flat side engages the flat side of the lug 39, and under this condition the outer door cannot be opened. The latch may then be retracted to permit 85 the opening of the outer door by forcing inwardly the plunger whereby the latch 25, is retracted into the position shown in Fig. 3, and is held in such position by the plunger, which in the same movement has lifted 90 the latch-reset 26, into full shot position. Under this condition, the outer door may be swung open and the cylinder revolved a half circle, and during this movement of the cylinder the inclined face of the lug 40 col- 95 lides with the inclined face of the reset 26, with sufficient force to fully depress it there- by forcing the plunger outwardly, by virtue of the inclined part 36, on the lug 37, sliding over the incline 35, of the plunger, 100 and this movement at the same time carries the plunger away from the lug 31, on the latch 25, and permits said latch to move into shot position. When the parts are in this position with the door open the flat part 105 of the latch 25 is engaged by the lug 41 thereby preventing the cylinder from swing- 110 ing through more than a half circle. If the door now be closed the cylinder is swung back through its half circle movement and the inclined part of the lug 39, comes in contact with the bevel of the latch 25, so that the continued movement of the cylin- 115 der depresses the latch and permits the lug to snap by it into the position shown in Fig. 1, thereby bringing the flat parts of the latch and lug together and locking the cylinder in this position with the door closed and preventing a second opening of the door. The door cannot be opened again 120 until the plunger is forced inwardly by means of its handle so as to depress the latch 25, as hereinbefore described. When the door is closed the flat part of the lug 40, on the bottom of the cylinder lies in 125 contact with the fixed lug 42, on the bottom of the inclosing casing 1, thereby pre- venting any further movement of the cylin-

der on its axis which might occur by the slight play which the cylinder would have by the sudden closing of the door.

The opening of the inclosing casing which is exposed upon the interior of the wall is provided with a removable frame 45, which is hinged at 46, to the casing and is provided with a lock 47. This frame is formed with an inwardly projecting flange 48, which fills the space up to the curved wall of the receptacle and at its upper and lower parts it is cut away as at 49, to conform to the cylindrical shape of the receptacle.

The inclosing casing may be made of suitable sheet metal as indicated in the drawings of wood or other material and it may be shaped to suit the taste.

In the construction of the device herewith shown I have illustrated its use in the wall of a frame house and in the drawings I have illustrated the usual frame structure in such a house. The device of course may also be used in a structure of stone, brick or other material, the outer casing of the device to be built into the wall in a suitable manner.

I wish to be understood as not limiting my invention to the exact construction of the various different parts as herewith shown, as various modifications may be made in the same, without however departing from the spirit of my invention.

Having thus described my invention what I claim and desire to secure by Letters Patent is:

1. In a safety delivery cabinet of the class described, the combination of a revoluble receptacle having a hand-opening in its side and adapted to be mounted in an opening in a wall, an exterior door for closing said opening and connections between said door and receptacle whereby the opening of said door turns the receptacle so as to bring the hand-opening thereof to the exterior and the closing of said door brings the hand opening to the interior side of said wall, and locking means controlling said receptacle and door and provided with a device for setting said means in unlocked position from the interior side of the wall and automatically locking said receptacle and door upon the closing of the door, whereby the said door cannot be opened until the locking means is reset.

2. In a safety delivery cabinet of the class described, the combination of a revoluble receptacle having a hand-opening in its side and adapted to be mounted in an opening in a wall, an exterior door for closing said opening, a link pivoted between said door and receptacle and serving to rotate the receptacle in response to the movement of the door, and locking means controlling said receptacle and door and provided with a device for setting said means in unlocked po-

sition from the interior side of the wall and automatically locking said receptacle and door upon the closing of the door, whereby the said door cannot be opened until the locking means is reset.

3. In a safety delivery cabinet of the class described the combination of a revoluble receptacle having a hand-opening in its side and adapted to be mounted in an opening in a wall, an exterior door for closing said opening and connections between said door and receptacle whereby the opening of said door turns the receptacle so as to bring the hand-opening thereof to the exterior and the closing of said door brings the hand-open-

ing to the interior side of said wall, and locking means controlling said receptacle and door and capable of being set from the interior side of the wall to permit of the door being opened from the exterior and

serving to lock said parts when the door is subsequently closed to prevent another successive opening of the exterior door, said locking means comprising a spring actuated latch normally in shot position, a stop nor-

mally engaging said latch and holding the receptacle against rotation, an automatic re-set for said latch normally retracted, a plunger operated from the interior side of the wall and acting when forced in one di-

rection to retract the latch and project the reset, and a trip device adapted to collide with the projected reset when the receptacle is being turned into opening position and to retract said reset and thereby move the latch into shot position.

4. In a safety delivery cabinet of the class described, the combination of a revoluble receptacle having a hand-opening in its side and adapted to be mounted in an opening in a wall, an exterior door for closing said opening and connections between said door and receptacle whereby the opening of said door turns the receptacle so as to bring the hand-opening thereof to the exterior and

the closing of said door brings the hand-opening to the interior side of said wall, and locking means controlling said receptacle and door and capable of being set from the interior side of the wall, to permit of the door being opened from the exterior and

serving to lock said parts when the door is subsequently closed to prevent another successive opening of the exterior door, said locking means, comprising a spring actuated latch normally in shot position, a stop nor-

mally engaging said latch and holding the receptacle against rotation, an automatic re-set for said latch normally retracted, a plunger operated from the interior side of the wall and acting when forced in one di-

rection to retract the latch and project the reset, and a trip device adapted to collide with the projected reset when the receptacle is being turned into open position and to

retract said reset and thereby move the latch into shot position, and a stop for engaging the said latch when projected by the reset to limit further forward rotation of said receptacle.

5. In a safety delivery cabinet of the class described, the combination of a revoluble receptacle having a hand-opening in its side and adapted to be mounted in an opening in 10 a wall, an exterior door for closing said opening and connections between said door and receptacle whereby the opening of said door turns the receptacle so as to bring the hand-opening thereof to the exterior and the 15 closing of said door brings the hand-opening to the interior side of said wall, and locking means controlling said receptacle and door and capable of being set from the interior side of the wall to permit of the door being 20 opened from the exterior and serving to lock said parts when the door is subsequently closed to prevent another successive opening of the exterior door, said locking means comprising a spring actuated latch normally in 25 shot position, a stop normally engaging said latch holding the receptacle against rotation, an automatic reset for said latch normally retracted, a plunger operated from the interior side of the wall and acting when 30 forced in one direction to retract the latch and project the reset, and a trip device adapted to collide with the projected reset when the receptacle is being turned into open position and to retract said reset and there- 35 by move the latch into shot position, and a stop for engaging said trip device upon the return movement of the receptacle and limiting the backward movement thereof.

6. In a safety delivery cabinet of the class 40 described the combination of a revoluble receptacle having a hand-opening in its side and adapted to be mounted in an opening in a wall, an exterior door for closing said opening and connections between said door 45 and receptacle whereby the opening of said door turns the receptacle so as to bring the hand-opening thereof to the exterior and the closing of said door brings the hand-opening to the interior side of said wall, and 50 locking means controlling said receptacle and door and capable of being set from the interior side of the wall to permit of the door being opened from the exterior and serving to lock said parts when the door is 55 subsequently closed to prevent another successive opening of the exterior door, said locking means comprising a spring actuated latch normally shot, a projection on said latch, a reciprocating plunger engaging the 60 projection on said latch and acting to retract the latch when slid over said projection by the movement of the plunger, an automatic reset operatively connected with the latch and moving in a reverse direction and 65 normally retracted, a lug on said reset en-

gaged by said plunger in its inward movement for projecting the reset, a trip-device adapted to collide with the reset to retract it in the forward rotation of the receptacle, and a stop for engaging said latch when 70 reset in the forward rotation of the receptacle.

7. In a safety delivery cabinet of the class described, the combination of a revoluble receptacle having a hand-opening in its 75 side and adapted to be mounted in an opening in a wall, an exterior door for closing said opening and connections between said door and receptacle whereby the opening of said door turns the receptacle so as to bring 80 the hand-opening thereof to the exterior and the closing of said door brings the hand-opening to the interior side of said wall, and locking means controlling said receptacle and door and capable of being set from the 85 interior side of the wall to permit of the door being opened from the exterior and serving to lock said parts when the door is subsequently closed to prevent another successive opening of the exterior door, said 90 locking means comprising a spring actuated latch normally shot and provided with a projection having an inclined face, a reciprocating plunger provided with an inclined face coöperating with the said inclined face of the latch-projection, an automatic reset having a lug provided with an inclined face, said plunger being provided with a second inclined face coöperating with that on said reset lug whereby the inward 95 movement of said plunger retracts the latch and projects the reset and the forcing in of the reset returns the plunger and causes it to shoot the latch, a trip-device for colliding with and actuating said reset in the forward rotation of the receptacle and a stop 100 limiting the backward rotation of the receptacle when the latch is shot.

8. A safety delivery apparatus having a receptacle constructed and arranged to turn 110 on an axis, an outer door controlling access to said receptacle, means for positively connecting said receptacle and outer door, means for locking the receptacle, whereby said locking means serves to lock both said 115 receptacle and outer door, substantially as described.

9. A safety delivery apparatus having a receptacle constructed and arranged to turn on an axis, an outer door controlling access 120 to said receptacle, means acting to turn said receptacle in response to the opening and closing movements of said outer door, means for locking said receptacle, whereby said locking means serves to lock both said 125 receptacle and outer door, said locking means being arranged for manual release from a point to the inside of said outer door and to be locked by the closing of said outer door, substantially as described.

10. A safety delivery apparatus having a receptacle constructed and arranged to turn on an axis, an outer door controlling access to said receptacle, means connecting 5 said receptacle and outer door constructed and arranged so as to turn said receptacle by the opening and closing movements of the said outer door, locking-means controlling said receptacle and outer door and arranged for 10 manual release at a point within said outer door, and means for resetting automatically said locking-means upon closing of the said outer door, substantially as described.
- 15 11. A safety delivery apparatus having a receptacle constructed and arranged to turn on an axis, an outer door controlling access to said receptacle, means connecting said re-
- ceptacle and outer door constructed and arranged so as to turn said receptacle by the 20 opening and closing movements of said outer door, locking-means controlling said receptacle and outer door and arranged for manual release at a point within said outer door, and means for resetting automatically 25 said locking-means upon closing of the said outer door, said resetting means being actuated by the movement of said receptacle, substantially as described.

In testimony whereof, I have hereunto 30 set my hand in the presence of the two subscribing witnesses.

RICHARD K. MOSLEY.
